UNITED STATES PATENT OFFICE.

HENRY M. WILLIAMS, OF FORT WAYNE, INDIANA, ASSIGNOR OF ONE-FOURTH TO FRANZ BURGER, OF SAME PLACE.

DESIGN FOR A SPOON.

SPECIFICATION forming part of Design No. 28,788, dated June 7, 1898.

Application filed January 13, 1898. Serial No. 666,573. Term of patent 14 years.

To all whom it may concern:

Be it known that I, HENRY M. WILLIAMS, a citizen of the United States, residing at Fort Wayne, in the county of Allen and State of Indiana, have invented and produced a new and original Design for Spoons, of which the following is a specification, reference being had to the accompanying drawings, forming part thereof.

10 Figure 1 is a plan view of a spoon embodying the design, and Fig. 2 is a side view of the same.

15 The leading features of my design consist in the shape or configuration of the bowl or body A of the article, and, as shown in Fig. 1, the bowl or body A presents an outline embracing four curves joined at their ends, showing a bowl or body having four rounded extensions a, with indentations b between them, and

these extensions have on their under sides 20 rounded or curved outlines merging into each other, as shown at c, Fig. 2, and from one of the extensions projects the handle E.

The general appearance of the design presents a bowl or body embracing four curved 25 and rounded extensions merging into each other, from one of which extensions projects a handle.

What I claim is—

The design for a spoon or similar article 30 substantially as shown and described.

In testimony whereof I have signed my name to this specification in the presence of two subscribing witnesses.

HENRY M. WILLIAMS.

Witnesses:

E. W. COOKE,
J. BURGER.
